SYRINGE

Filed May 29, 1928

Louis F. Narz ^{Inventor}

By his Attorney
George C. Heinrich

UNITED STATES PATENT OFFICE

LOUIS F. NOVAK, OF JERSEY CITY, NEW JERSEY

SYRINGE

Application filed May 29, 1928. Serial No. 281,495.

My invention relates to improvements in syringes, particularly in vaginal syringes, and the primary object of my invention is the provision of a syringe of this character embodying means to provide a whirling cleansing spray forward, and including a novel air duct arrangement to permit the drawing of air into the vaginal canal as the syringe is being withdrawn in order to create a suctional effect and to eliminate the formation of a vacuum which is harmful to the inner organs.

Another object of my invention is the provision of a syringe of this type of comparatively simple and inexpensive construction, yet durable and positive, as well as efficient in its operation.

These and other objects and advantages of my invention will become more fully apparent as the description thereof proceeds, and will then be specifically defined in the appended claims.

In the accompanying drawing forming a material part of this disclosure:

25 Fig. 1 is a side elevation of a syringe constructed according to my invention, partly in section to disclose the interior construction thereof.

30 Fig. 2 is a cross-section through the forward part of the syringe on line 2—2 of Figure 1, with the sprayer nozzle uncovered.

Fig. 3 is a section on line 3—3 of Figure 2.

35 Fig. 4 is a face view of a disc seen in the direction of arrows 4—4 of Figure 3.

Fig. 5 is a fragmentary outside view of the inlet and outlet tube.

Fig. 6 shows a modified form of air duct.

Fig. 7 illustrates a cap.

40 As illustrated, my novel and improved syringe consists of the generally well known collapsible rubber bulb to the neck part 11 of which is detachably or otherwise secured the slightly curved main inlet- and outlet-tube 12, for instance in the manner illustrated in Figure 1, which may be of hard rubber or any other suitable material.

45 The front end of this tube is closed by a rubber nozzle or nipple 13 having an inner thread adapted to be engaged by the outer

thread on the end of an inner air duct or tube 14 preferably of metal, and arranged within the tube 12 substantially following the longitudinal axis thereof however approaching the wall of the tube 12 near its 55 inner end and having an angular passage-way or duct 15 at its extreme inner end extending through a corresponding opening in the outer tube 12 underneath a guard 16 supported on the main tube 12 and forming an 60 air pocket 17 with which said duct 15 communicates.

The guard member 16 rests with its inner apex against a collar 18 on main tube 12 in which the opening of duct 14 is located. 65 The outer end of the neck 11 of the rubber bulb rests against the outer face of this collar 18, and the open inner end of main tube 12 is provided with a flaring mouth 19 holding the bulb on said main tube and communicating with the bulb, while the neck part 11 of bulb 10 is adapted to be expanded over the rear end of main tube 12 as shown in Figure 1.

70 The nipple 13 is covered by an outer soft 75 rubber cap 20, perforated or not.

At a certain distance from the end of main tube 12 the inner tube 14 carries a disc 21 within tube 12 having a plurality of radially extending slots 22 formed therein co-operating with another disc 23 substantially in the shape of a turbine wheel and loosely supported on inner tube 14 having a plurality of blades 24 formed therewith as best shown in Figure 3 forming buckets 25 80 or the like and provided with openings 26 co-operatively arranged to openings or slots 22 in disc 21.

85 My device operates as follows: Upon alternately and intermittently exerted pressures on the bulb the cleaning fluid will be squirted into tube 12 in the direction of the arrows in Figure 3 and through the openings 22 in the stationary disc 21 will impinge through openings 26 against the turbine 90 buckets of disc 23 and whirl the same, so the cleansing fluid will enter the vagina as a whirling spray adapted to produce a thorough cleaning of all parts. It will be clear 95 that the provision of the slightly curved air 100

duct will permit air to be drawn into the vaginal canal so that the creation of a harmful vacuum during the withdrawal of the syringe is effectively prevented.

In the modified form of my invention illustrated in Figure 6, the air duct is shortened and straight, as shown, or can be omitted and replaced by a stud or screw 27 or the like having a central bore and providing an air duct, and supporting the discs and the tip of the nozzle, otherwise the construction is the same as described above with respect to the preferred form.

It will be understood that I have shown as examples of the many ways in which my syringe may be practically constructed the preferred forms thereof only, and that I may make such changes as come within the scope of the appended claims in the general arrangement and in the construction of the minor details of my invention without departure from the spirit of my invention and the principle involved.

Having thus described my invention, what I claim as new, and desire to secure by Letters Patent is:

1. In a vaginal syringe, the combination of a main tube, having a collapsible bulb at one of its ends and a nozzle at the opposite end thereof, with an air vent tube within said main tube carrying the nozzle at one end and communicating with the atmosphere at its other end, a disc on said air vent tube at a distance from the mouth of said main tube, said disc having a plurality of radial openings, another disc rotatably held on said air vent tube in front of said first named disc, said second disc provided with openings communicating with the openings in said first named disc, turbine buckets on said second disc adapted to be rotated by the cleansing fluid pressed by said bulb through the main tube and issuing from said nozzle to impart to said fluid a whirling cleansing motion to reach all parts of the vagina, and means allowing the introduction of air into the vagina during the withdrawal of the syringe preventing the formation of a vacuum within the organ.

2. A vaginal syringe comprising a collapsible bulb, a curved main tube connected to said bulb, a seat formed at the outer end of said main tube, a means for imparting to the fluid a forwardly directed whirling, a short straight air vent tube extending into the outer end of said main tube, and projecting therefrom, a nipple on the outer end of said tube, forming with said seat a nozzle, for issuing the fluid under the pressure of said bulb in a whirling cleansing spray, said straight tube acting as a support for the nozzle.

3. A vaginal syringe comprising a main tube having a collapsible bulb at one of its ends, and a nozzle at the opposite end there-

of, a short straight air vent tube extending into said main tube carrying said nozzle, a slotted disc on said vent tube, a rotary disc on said vent tube, co-operating with said slotted disc to impart to the cleaning fluid issuing through said nozzle, a whirling action upon the compression of said bulb, and a means for leading air into the vaginal canal during the withdrawal of the syringe from the vagina.

4. In a vaginal syringe the combination of a main tube having a passageway therethrough open at opposite ends of the tube, a collapsible bulb attached at one end to said tube, a nozzle supporter at the opposite end of the said tube, a short air vent tube extending longitudinally in the passageway of said main tube and having an air inlet at the rear end thereof, said air vent tube having an exit at the front end thereof at the extreme top of said nozzle, said air vent tube allowing the introduction of air upon the withdrawal of the syringe from the vagina, and a means to impart to the cleaning fluid a whirling motion during its issue from said nozzle upon the compression of said bulb.

Signed at New York, in the county of New York and State of New York, this 21st day of May, A. D. 1928.

LOUIS F. NOVAK.
